UNITED STATES PATENT OFFICE.

ROBERT H. BROWN, OF ELK RIDGE LANDING, MARYLAND.

DESIGN FOR A SHOW-BOX FOR BOTTLES.

SPECIFICATION forming part of Design No. 14,253, dated September 4, 1883.

Application filed August 1, 1883. Term of patent 3½ years.

To all whom it may concern:

Be it known that I, ROBERT H. BROWN, a citizen of the United States, residing at Elk Ridge Landing, in the county of Howard and State of Maryland, have invented and produced a new and original Design for Show-Boxes for Bottles, of which the following is a specification, reference being had to the accompanying drawing, forming a part hereof.

10 The said drawing is a perspective view of my newly-invented show-box.

The leading feature of my design consists in combining with inclined side columns having shelves for bottles three vertical shelved columns placed in their rear, with the outer ones inclined back so as to throw the angle of the square shelves in front, and in surmounting the said three columns with an angular cap and a stand for a bottle, as will hereinafter 20 fully appear.

A is the base of the box, which is of rectangular form. B B are the inclined shelved

columns. C, D, and E are the vertical shelved columns, the ones C and E, which are connected to the central one, D, being thrown back so 25 as to bring a corner of the shelves to the front. F is the cap-piece, and G a stand for a bottle, secured to its upper side. The shelves on the column D are connected to the back by means of ornamental brackets a.

30 It will be understood that the design is for the box when opened, so as to display its contents.

I claim—

The design for a show-box for bottles here- 35 in shown and described, the same consisting of the inclined shelved columns B B, with the rear vertical shelved columns, C, D, and E, having the outer ones, C and E, thrown back, and surmounted by the cap F.

ROBERT H. BROWN.
